UNITED STATES PATENT OFFICE.

LOWRY S. KIRKER, OF PITTSBURG, PENNSYLVANIA.

GAS-ENGINE.

SPECIFICATION forming part of Letters Patent No. 627,338, dated June 20, 1899.

Application filed August 20, 1898. Serial No. 689,099. (No model.)

To all whom it may concern:

Be it known that I, LOWRY S. KIRKER, a citizen of the United States, residing at Pittsburgh, in the county of Allegheny and State of Pennsylvania, have invented or discovered a new and useful Improvement in Gas-Engines, of which the following is a full, clear, and exact description, reference being had to the accompanying drawings, forming part of this specification, in which—

Figure 1 is a view in side elevation, partly in section, of my improved engine. Fig. 2 is a plan view with a corresponding sectional portion. Fig. 3 is an end elevation. Fig. 4 is a cross-section on an enlarged scale, indicated by the line IV IV of Fig. 2. Fig. 5 is a detail sectional view of the igniting device and actuating mechanism. Fig. 6 is a similar view illustrating the insulation of the rods. Fig. 7 is a view in side elevation of the valve actuating and governing mechanism. Fig. 8 is a plan view of Fig. 7. Fig. 9 is an end elevation, partly in section, of the governor and its operative connections with the valve-lever shaft. Fig. 10 is a central longitudinal section through the pistons and water-cooled rod. Fig. 11 is an end view. Fig. 12 is a cross-section on the line XII XII of Fig. 10. Fig. 13 is a similar view on the line XIII XIII of Fig. 10. Fig. 14 is a cross-section on line XIV XIV of Fig. 1. Fig. 15 is a face view of the cam-shaft clutch. Fig. 16 is a similar view from the opposite side. Fig. 17 is a longitudinal sectional view thereof.

My invention relates to explosive-engines; and its object is to secure more regular action of the engine, with less friction, by means of more frequent impulses upon the piston, better regulation of the valves through an improved governing mechanism, and cooling of the engine-cylinders, valves, and piston by water circulation.

In general terms the engine consists of two main cylinders mounted on a bed-plate, pistons mounted in the cylinders on a common piston-rod connected with the cross-head, and the usual connecting-rod, crank, and main shaft, with means for admitting explosive elements to chambers at each end of each cylinder and suitable valve-gearing whereby a cycle of explosions is produced. The operations of explosion, discharge, suction, and

compression are performed in succession, so as to provide an impulse for the piston-rod at each half-stroke, four explosions occurring 55 during two revolutions of the crank, each in a separate chamber and acting on different faces of the pistons.

Referring now to the drawings, 2 is the main frame, upon which are mounted the cylinders 3 3. Each cylinder is composed of a middle internally-finished piston-chamber 4 and oppositely-located internally-unfinished explosion-chambers 5 5, the three parts being interfitting and secured together by bolts 6, 60 passing entirely through from end to end and securely held by nuts. For the purpose of cooling the cylinders water-circulation passages 7 are made in the walls of the piston and explosion chambers, which passages are 65 continuous from end to end when the cylinder is joined, and each end is inclosed by a cap 8, thus confining the water.

Along the interior of the bed-plate in any convenient position are located main water 75 supply and exhaust pipes 9 10, while branch pipes 11, connected with pipe 9, supply water to the cylinders, and pipes 12 convey the exhaust therefrom to pipe 10 or any convenient discharging-point. The pistons and rod are 80 built up in the manner shown in Figs. 10 to 13, inclusive, with circulating-water spaces whereby the entire piston structure is kept cooled through a circulation of water.

Each piston 13 is cast with a hollow internal chamber 14, while the forward piston is made with an extended hollow pipe-like stem 15, which forms the main piston-rod. Between the piston-heads extends a similar hollow stem or sleeve 16, screwed into lugs formed 90 on the faces of the piston-heads and by which they are rigidly held together.

Extending entirely through the sleeves 15 and 16 is an internal steel pipe 17, which at the forward end is tapped into the cross-head 95 18, while a nut 19 is screwed upon the other end, thus tightly clamping the parts together when in position and forming a strong rigid construction. It will be seen that between the pipe 17 and the inclosing sleeves 15 16 100 there is an intervening space 20, which is utilized for water circulation. Through the outer sleeve 15 and into pipe 17, at a point adjacent to the cross-head, is tapped a pipe 21,

provided with a flexible hose connection 22, leading from any source of supply, while a similar pipe 23 is tapped into the outer sleeve 15 and is furnished with a hose 24, leading to any point of discharge. At its outer end the pipe 17 is provided with ports 25, whereby incoming water will travel the entire length of the pipe and then after passing through ports 25 will return by passage 20 to pipe 23 and escape through hose 24. By means of these flexible connections the piston structure is kept cooled during the operation of the engine.

The cylinders are equipped with stuffing-boxes 26, by which packing is provided for the piston-rod, the outer sleeves thereof having been turned smooth for such purpose. The cross-head 18 is mounted in suitable slides 27 on the bed-plate and is connected in the usual manner with the crank by connecting-rod 28. Mounted in the upper side of each explosion-chamber are the gas-inlet-valve chambers 29, having an interior cavity 30, leading into the explosion-chamber 5. A valve 31 is mounted on the end of a stem 32, provided with a spring 33, by which the valve is normally held closed on the seat of the valve-chamber. A similar exhaust-valve chamber 34 is mounted in the lower side of each explosion-chamber, with a cavity 30' and an upward sleeve extension 35, within which is slidably mounted the valve-stem 36, also having a retracting-spring 33', by which the valve 37 is normally held closed on its seat. Into the cavity 30' is introduced a branch pipe 38, leading from the water-supply main 9, while an enlarged pipe 39 conveys away the waste water and also products of combustion to exhaust pipe 10.

Projecting into each explosion-chamber is an igniter-plug 40, within which is mounted a stationary terminal rod 41, having at its inner end an arm 42, within which is carried a contact-pin 43, driven into the arm 42 with a tight fit. Mounted in line with the pin 43 is a slidingly-mounted rod 44, adapted to make contact with the pin and produce a spark to ignite the gas. Each rod is surrounded by insulation 45 and wires 46 47, leading to the poles of a battery or source of electrical energy. It will be seen that the current to and from the igniter-rods is carried through independent wires connected with the poles of the battery, thus avoiding the objectionable feature of making a ground connection to any part of the engine.

The inlet-valve chambers are supplied with gas and air in suitable proportions through pipe 48 and port 49, respectively.

The inlet-valves 31 are depressed, to admit the admixture, by arms 50, pivoted to a rod 51, mounted at its ends in arms 52, which arms are secured to a rock-shaft 53, mounted in suitable bearings 54, while the rod 51 is engaged in guiding-slots 55. One of the arms 52 is provided with an extension 52', which is connected by link 52" to the vertically-slid-

ing portion of a governor A, geared in the usual manner with the engine.

As the speed of the engine varies the pivotal rod 51 is raised and lowered, thus raising 70 and lowering the fulcrum of the valve-lever and rendering its effective operation dependent on the varying speed of the engine.

The outer end of arm 50 is attached to a rod 56, mounted in bearing 57 and provided at its lower end with a roller 58, resting on an actuating-cam 59 on a common cam-shaft 60'. This cam-shaft is mounted in bearings 61 upon a shelf 62, projecting out laterally from the engine, and is geared by bevel-wheels 63 64 80 with the main shaft, so as to make one revolution during two revolutions of the main shaft, corresponding to four strokes of the piston. In this manner each of the inlet-valves will be operated in succession, the 85 cams being set on the shaft in proper relation to actuate the lever-arms 50 at the proper moment. In a similar manner the spark is produced by action of a lever-arm 65, pivoted at 66, engaging the upper end of rod 44 and 90 provided with a roller 67, bearing on cam 68, the contacts and ignitions being produced in a series corresponding to the action of the inlet-valves. The outlet-valves are operated in like manner, following the explosion at the 95 proper interval, through bell-crank lever 69, link 70, and lever 71, having mounted on its upper end the roller 72, adapted to bear against the cam 73 on shaft 60'. It will thus be seen that the valves and igniters are all 100 operated from one cam-shaft, and I am thus enabled to set the cams very accurately, so as to operate at the right time.

In the operation of explosive-engines I have found that at full speed it is desirable to actuate the valves and igniter at a time with relation to the travel of the piston somewhat sooner than when the engine is starting or at slow speed, and I have therefore devised a means for setting all of the cams forward at 105 one time by a partial revolution after the engine is started. To this end the cam-shaft 60' is made in two sections, to the outer one of which (60') the cams are secured. Between the sections is a coupling device consisting 110 of a head 74, secured to the inner portion of the shaft 60, and a head 75, slidingly mounted by a spline to the other portion of the shaft 60', bearing the cams. Secured to each head is a coiled spring 76, adapted to rotate the 115 outer head and shaft a partial revolution, which travel is limited by the lug 77 coming into contact with the abutment 78 on the other head. Normally the heads are held together in engagement by pins 79 entering sockets 80 120 in head 74 and until sufficient speed is reached by the engine, when the head 75 is drawn outwardly by ring 81 against spring 82 abutting against washer 83, releasing the pins from engagement, and under action of spring 76 125 the cam portion of the shaft will rotate, carrying the cams around, which will in such

advanced position operate proportionately sooner, thus obviating the objections due to the speed of the engine crowding such operations. The circulation of water through the 5 exhaust-valve not only serves to keep it cool, but will absorb and deaden the sound, inasmuch as there is at all times a body of water contained in the lower portion of the valve in its passage therethrough.

10 The general arrangement of my engine and of the various parts contributing to its operation is very simple and compact, and it is designed to operate continuously without attention, and will commend itself to a large 15 class of users of this type of engine and for a wide variety of work.

Changes and alterations may be made in its details of construction by the skilled mechanic without departing from my invention, 20 as I do not desire to be limited to the exact construction shown in the drawings.

Having described my invention, what I claim, and desire to secure by Letters Patent, 25 is—

25 1. In a gas-engine, the combination of two alining water-cooled cylinders composed of middle and end sections respectively secured together, pistons therein mounted on a common piston-rod, means for maintaining a wa- 30 ter circulation through the pistons and rod, explosion-chambers in each of the end sections of the cylinders provided with an upper gas and air inlet valve, a lower exhaust-valve with means for maintaining a water circula-

tion therethrough, an igniting device in each 35 explosion-chamber, and means for operating the valves and igniting devices, substantially as set forth.

2. A gas-engine comprising two cylinders mounted in alinement, each cylinder having 40 a middle piston-chamber and separate explosion-chambers at each end, continuous water-circulation passages extending through the side walls of the cylinders from end to end with common inclosing chambers at each end; 45 means for securing the middle and end sections of the cylinder together, water-cooled pistons in each cylinder mounted on a common water-cooled piston-rod, inlet-valves at each end of each cylinder, corresponding outlet-valves at each end of each cylinder provided with water supply and exhaust pipes, 50 igniting devices at each end of each cylinder, means for operating such valves and igniting devices and a series of actuating-cams there- 55 for mounted on a common cam-shaft made in two sections with a connecting-joint permitting a partial rotation of one section of the shaft upon which the cams are mounted with relation to the other section, substantially as 60 set forth.

In testimony whereof I have hereunto set my hand.

LOWRY S. KIRKER.
